GAME BOARD APPARATUS

Alan Charles and David Charles, both of 35 W. 9th St.,
New York, N.Y. 10011
Filed July 17, 1964, Ser. No. 383,314
3 Claims. (Cl. 273—134)

ABSTRACT OF THE DISCLOSURE

A board having a central area with a plurality of player starting squares and a peripheral area enclosing the central area with marked spaces constituting a playing course. Playing tokens commencing from the starting squares are advanced around the playing course, by chance means, such as dice. Certain of the marked spaces indicate a penalty and others indicate that the player is to select a card from a specific set of cards. A plurality of sets of cards is used, each set relating to a different category of goods. Each set of cards is marked with a different color and each card within a set is marked with the same color. Further, each card in a set has a different point count. Disposed along at least two side edges of the board are strips substantially parallel to the side edges of the board and disposed exteriorly of the playing course. The strips are divided into sections and each section contains indicia similar to that shown on one of the sets of cards. Each of the strip sections is marked with a different color which corresponds to the color of the set of cards having corresponding indicia. The sections in each strip indicate a number of items of goods corresponding to a "House" of the cards, and the player who first achieves the "House" is entitled to a bonus score in addition to the point score indicated on the individual cards making up the "House."

Summary of the invention

Our present invention seeks to provide a game board apparatus involving tokens, chance devices for moving them around the board, and card decks representing stated goods and/or services, most of which have a point value to the player acquiring them. It especially relates to means for associating acquired cards with indicated portions of the board which constitute a player's so-called "House." By means of the cards the player seeks to fill his House with acquired goods of the appropriate kind in accordance with the rules of the game. The invention also seeks to provide for the disposition of said indicated portions in a manner which will be of great convenience to the players without in any way interfering with the movement of the tokens around the playing course of the board.

In the embodiment herein shown and described, the game apparatus is directed to the subject of appliances, and through the medium of appropriately marked cards, a player seeks to furnish his House with such appliances which have the greatest point value.

In playing the same, the player advances his token upon the playing course of the board in accordance with the throw of the dice or by other chance device. In so moving, the token may come to rest upon marked areas which represent hazards, as well as rewards, or upon neutral areas which are neither one nor the other. For example, if he lands upon a space or square marked "Take a Portable TV," he thereupon draws a card of a category or deck so marked, and having done so, places the drawn card at the edge of the board upon a rectangle outside the playing course marked the same as that of the category to which the card belongs, such card thus constituting one element of his House. Or, he may meet

2

with a hazard or penalty which will require an entirely different action on his part.

For a more complete understanding of our improved game, reference may now be had to the following description of a specific embodiment thereof, taken with the annexed drawings, in which

FIGURE 1 is a plan view of the playing board;

FIGURE 2 is a view in perspective of a pair of dice used, and one of the several tokens required;

FIGURE 3 is a plan view of three playing cards showing the face of the cards in the left column, and the backs of the respective cards in the right column. These cards are exemplary of those of the complete deck or category of, say, twenty, the backs of the cards denoting the category of "Radio," of which the bottommost is a so-called "Show" card, the purpose of which will be explained hereinafter, whereas the faces of the cards indicate various types or models in the Radio category, and the point values corresponding thereto. In each deck one or more cards will either reward the player in a different way, or will subject him to a penalty. An example of this is the bottommost card of FIGURE 3 whose face is labeled "Wild Card" and directs the player to "Take Card From Any Deck You Choose." The purpose of other of such cards will be apparent.

FIGURE 4 is exemplary of a deck of twenty cards in the category "Phonograph";

Similarly, FIGURE 5 is exemplary of a deck of twenty cards in the category of "Console TV";

FIGURE 6 shows a similar deck in the category "Tape Recorder";

FIGURE 7 shows a similar deck in the category "Portable TV";

FIGURE 8 shows a similar deck in the category "Air Conditioner"; and

FIGURE 9 is exemplary of a deck of twenty cards in a special category designated "Appliance First," the purpose of which will be explained below.

Referring now to the drawings, and to FIGURE 1 in particular, our improved game apparatus includes a plane surface such as is afforded by a board 10, preferably of square shape, as shown. A peripheral playing course is composed of contiguous squares or blocks 12 extending around the board. Said squares 12 are variously marked as shown; for the most part they bid the player whose token comes to rest upon a particular square, e.g., "Take a Radio," to choose a card of a named category, whereby usually a gain for such player may be realized, though sometimes a loss, as for example, should he pick the bottom card of FIGURE 8 which bids the player to "Go to Elm Street." Other squares, as for example, those marked "Go to Grand Street" (or other street) have a similar effect without requiring the drawing of a card. All these directions require the player to put his token into one of the boxes or rectangles 14-17 so designated. It will be noted that each of said boxes is provided with a number from 3 to 6, and for the player to be able to move his token from the box, he must throw his number on the dice. Or a square may bid a player to "Give Back a Radio," or "Go Back Three Spaces," or exact some other penalty.

The board, which is adapted to accommodate from two to four players, has upon each side thereof a series of rectangles forming a border of the square represented by the board, which rectangles correspond in number and marking, and preferably in color, as shown, to the categories represented by the decks of cards illustrated in FIGURES 3-8 inclusive. These rectangles accordingly are marked "Radio," "Phonograph," "Console TV," "Tape Recorder," Air Conditioner," and Portable TV," such rectangles being numbered 20, 21, 22, 23, 24, 25

respectively; similar rectangles similarly labeled border the other three edges of the board, and have similar reference characters, save that on each side, different subscripts are used.

It is believed that a full understanding of our improved game apparatus will be had by the following description of the mode of playing the game represented by the board thus far described.

To begin, each of the seven decks is shuffled and placed face down, within reach of all the players. Each player's name is entered upon a score pad, not shown, and each player is given a token which will be placed initially in one of the boxes 14-17. To start the game, each player rolls the dice to determine who goes first. If two or more players tie, the roll is repeated. The player with the highest score then has first choice in the selecting the street sign from which he wants to start. The remaining players then select their starting streets (boxes 14-17) in the order of their position to the left of the highest scorer.

To put his token into play on the board, the player must roll the same number as is on his street sign, i.e., represented by boxes 14 to 17. Since chances favor the rolling of a high number rather than a low one, the player starting on State Street, No. 6, thus starts with a slight advantage. When a player rolls the right number to get out of his street sign or box, he moves his token radially outwardly from his starting street in the direction of the arrow extending outwardly from the street to a block 12 at a corner of the board next to the street. He advances his token from the corner block 12 in a clockwise direction the number of squares equal to the number rolled on the dice. The tokens are moved from the starting areas to corner squares 12 and along the course in accordance with prescribed rules.

When a player rolls a pair (both dice showing the same number), he moves his token as directed and follows the instructions given on the block 12 on which he lands, and then rolls the dice again. If he rolls another pair, he has another turn, thus rolling a third time. If he rolls a pair a third time, he must move his token to Grand Street, No. 3, and pass the dice to the next player.

The rectangles 20-25, disposed upon a given side of the board, are under the jurisdiction of the player sitting opposite such rectangles, and are collectively designated a "House." In order to win the game, a player must fill his House with the appliances called for. For instance, if a player's token lands upon a square labeled "Take a Portable TV," he thereupon has the privilege of drawing the top card of the deck so marked. Having done so, he places the card in the rectangle so marked in front of him, with the body of the card resting both on the rectangle and upon the surface of the table upon which the board is placed. If he already holds a card in that category, he will take the card of higher point value and return the other to the bottom of the deck from which it came. If a player exchanges a card he already holds for one he has drawn, he is "trading up," and must so state to the other players. On the other hand, if a player's token comes to rest upon a square bearing the legend "Just Shopping," he sustains neither a gain nor a loss, and simply waits until his next turn at the dice to move his token. Or, if a player's token comes to rest upon a square marked "Give Back a Console TV" or other appliance, he thereupon places the card, if such he has, face down on the bottom of the appropriate deck. If he does not have the appliance card to give back, he is exempt from the penalty, and awaits his next turn.

If a player lands on a block already occupied by another person's token, he gets no penalty or award as indicated on the block, but leaves his token there and awaits his next turn at the dice. If a player lands on a block 12 with the instructions to draw a card marked "Appliance First," or he draws a card marked "Take an Appliance First" (see FIG. 7), he is entitled to take only one of the

cards marked as shown in FIGURE 9, and he may use the stated value of the card as additional points toward his total score, or, if the card is marked "2-Way," as shown in FIGURE 9, he may either use the points as just mentioned, or use the card in filling out his House.

If a player draws a card marked "Show," he must exhibit it to the other players; otherwise cards drawn by a player are not disclosed to the others. The "Show" cards, which may be either penalty or bonus cards, are returned face down at the bottom of the deck from which they are drawn, and may not be held by any player.

Having filled out his House with the appliances called for by the squares 20-25, a player may indicate his intention to go out, and thereby get a 50-point bonus. However, to win the game, he must have a higher total score than any other player. Once the player has declared his intention to go out, all players total up their cards, and the player with the highest point score, whether he has a full House or not, is the winner. For this reason, a player with a full House may decide not to declare his intention to go out if he thinks his total score is not high enough to win. Also, after a player has declared his intention to go out, he must wait until all players have had one more chance at the dice, except only if his last roll was a pair.

It will be noted that because the player will quickly become familiar with the goods and/or services dealt with, such game apparatus will readily serve as a vehicle for the pictorial and verbal exhibition and display of related goods and services of a wide variety; hence it is of utility in the advertising art.

Also, it will be apparent that various changes may be made in the arrangements of board and cards within the scope and spirit of our invention.

We claim:

1. A board game apparatus for evaluating the point value assigned to specific items of goods in a point score game which is won by the player having the largest total number of points shown on cards after at least one of the players collects a "house" comprising a group of said cards, said apparatus comprising a board having a central area with a plurality of player starting squares, said board having a peripheral area around the central area with marked spaces constituting a playing course extending around the board along which playing tokens are advanced by chance means from said starting squares, each of said starting squares being located adjacent a separate one of said marked spaces to facilitate movement from said starting space to a corresponding one of said marked spaces, a plurality of sets of cards, certain of said marked spaces having a penalty indicated thereon and other of said marked spaces having an indication directing the player to select a card from a specified one of said plurality of sets of cards, said penalty-marked spaces and said card selection-marked spaces being intermingled throughout the course, each of said plurality of sets of cards having data printed on the face thereof relating to a different particular category of goods, each said set of cards being marked with a different color and each card within a said set of cards being marked with the same color, said cards of each set each containing a different point count, said board having each of at least two side edges provided with a strip substantially parallel to the side edge of said board and exterior of said course and divided into sections each bearing indicia corresponding to one of said categories of goods, each of said strip sections being of a different color corresponding to the color of the said set of cards bearing the corresponding indicia, said sections in each strip having separate sets indicated thereon in a number corresponding to a "house" of said cards, whereby the player first achieving the "house" is entitled to a bonus point score in addition to the point score of the points indicated on the "house" of said cards.

2. A board game apparatus according to claim 1 in which said board is substantially square in shape, and each side of which is provided with a said strip.

3. A board game apparatus according to claim 1 in which the said sections of each strip are of a length substantially the width of the cards, and of a depth substantially less than the length of the cards to be associated therewith.
